UNITED STATES PATENT OFFICE.

LOUIS MAYER, OF KAUKAUNA, WISCONSIN.

HAMMER.

1,386,891.

Specification of Letters Patent. Patented Aug. 9, 1921.

Application filed March 6, 1920. Serial No. 363,902.

To all whom it may concern:

Be it known that I, LOUIS MAYER, a citizen of the United States, and resident of Kaukauna, in the county of Outagamie and 5 State of Wisconsin, have invented certain new and useful Improvements in Hammers; and I do hereby declare that the following is a full, clear, and exact description thereof.

This invention relates to power hammers 10 and more specifically to the novel construction of parts comprising the anvil.

It is primarily an object of my invention to provide an arrangement whereby the working or cutting surface of the anvil may 15 be renewed upon wear.

A more specific object is the provision in an anvil of a detachable cutting die having a plurality of working surfaces adapted to be exposed in turn to the work.

20 With the above and other objects and advantages in view, which will be apparent as the description proceeds, my invention resides in the novel features of construction, combination and arrangement of parts, 25 which will be hereinafter more particularly described and defined by the appended claims.

In the accompanying drawing:

Figure 1 is a front elevation of a power 30 hammer embodying the features of my invention.

Fig. 2 is a detail sectional view through the anvil as indicated by the line 2-2 of Fig. 1.

35 Fig. 3 is a vertical sectional view through the anvil as indicated by the line 3-3 of Fig. 2, and

Fig. 4 is a perspective view of the cutting die.

40 Referring now more particularly to the accompanying drawing, 5 designates the anvil of the hammer, and reciprocative above this is the hammer head or ram 6. Mounted at the upper portion of the body 45 structure 7 is a crank wheel 8 on which is eccentrically mounted a pin 9 carrying a pitman link 10 on which is secured the sleeve 11, from which pivotally depends a pair of yoke arms 12 resiliently urged apart

50 by the spring 13 disposed between their intermediate portions. The lower ends of the yoke arms 12 are connected to the ram 6 by means of links 16, all of which structure is of a conventional nature and causes the 55 ram to be reciprocated.

The anvil 5 comprises a body member 17

provided with a recess 17' adjacent one of its ends and adapted to receive a rectangular cutting die 18. Secured to the body member by means of a bolt 19 is a retaining plate 20 which forms a closure wall for the open end of the recess 17'. The rectangular cutting die has its surfaces provided with centrally disposed tapered recesses 18' adapted to receive the tapered pins 21 carried by the body member and retaining plate. As best shown in Fig. 3, it will be noted that the tapered pins 21 are slightly off-centered with reference to the recesses 18' of the cutting die, thereby 70 causing the die to be wedged and rigidly secured within the recess 17' of the body member.

Inasmuch as this invention is specifically designed for the purpose of shaping, drawing and forming various kinds of tools, such as cold chisels, drills and the like, it will be noted as shown in Fig. 1 of the drawing that the abutting surfaces of the ram and anvil are suitably shaped for this purpose. 80 The result of these various forming and drawing operations is to leave an irregular shaped end upon the tool, and it is for the purpose of cutting and removing this irregular end that the cutting die 18 is provided. It will be readily understood that were the cutting die formed as an integral part of the anvil, the same would soon become dulled from the work, thereby rendering the entire member useless, and were a 90 die with a single cutting edge provided, the same would require frequent sharpening. For this reason it has been found preferable to use the rectangular cutting die 18 which, due to its shape, is provided with twelve cutting edges 18'', any one of which may be exposed to the work by merely shifting the position of the die within the recess of the body member.

As best shown in Fig. 3, the body member 100 17 is provided with a tool supporting surface 17'' adjacent the cutting die and flush with one surface of the same to form a support for a tool as indicated in dotted lines in Fig. 2.

105 While I have shown and described my invention in connection with an anvil of a power hammer, it will be readily understood that the same may be used in analogous machines, and may further be used in connection with a reciprocating member or ram, without departing from the invention.

I claim:

1. An anvil comprising a body member provided with a recess, a cutting die positioned within said recess, said die having a plurality of cutting edges adapted to be exposed in turn to the work, a retaining plate for securing the die to the body member, and means carried by the body member and retaining plate for holding the die into said recess.
2. An anvil comprising a body member provided with a recess, a die positioned within said recess and having a plurality of cutting edges adapted to be exposed in turn to the work, said die being provided with recesses, a retaining plate, and projections carried by the body member and retaining

plate adapted to engage the recesses in said die to wedge and lock the same securely to the body member.

3. An anvil comprising a body member provided with a recess, a rectangular die positioned within said recess and having a plurality of cutting edges, a retaining plate, means carried by the retaining plate and body member for holding the die in said recess, and a tool supporting surface provided in the body member, said surface being adjacent and flush with one of the die faces.

In testimony that I claim the foregoing I have hereunto set my hand at Kaukauna, in the county of Outagamie and State of Wisconsin.

LOUIS MAYER.
